Primary Examiner — Kevin Rudzinski(74) *Attorney, Agent, or Firm* — Harness, Dickey & Pierce, P.L.C.(57) **CLAIM**

We claim the ornamental design for a digital camera with a graphical user interface, as shown and described.

DESCRIPTION

The FIGURE is a front-side view of a digital camera with a graphical user interface showing our new design.

The broken lines shown in the drawings illustrate the digital camera and form no part of the claimed design.
